[57] CLAIM

The ornamental design for a stand for saddles, as shown and described.

DESCRIPTION

FIG. 1 is a top, front and left side perspective view of a stand for saddles showing my new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is perspective view of a second embodiment of FIG. 1;

FIG. 9 is a left side elevational view of FIG. 8;

FIG. 10 is a front elevational view of FIG. 8;

FIG. 11 is a right side elevational view of FIG. 8;

FIG. 12 is a rear elevational view of FIG. 8;

FIG. 13 is a top plan view of FIG. 8; and

FIG. 14 is a bottom plan view of FIG. 8.

FIG. 1.

FIG. 6.

FIG. 2.

FIG. 7.

FIG. 3.

FIG. 4.

FIG. 5.

FIG. 8.

FIG. 13.

FIG. 9.

FIG. 14.

FIG. 10.

FIG. 11.

FIG. 12.
